COMBINED DISPLAY AND MERCHANDISING RACK FOR LIPSTICKS OR THE LIKE

Rüdiger Behnke, Rhonstrasse 79, Frankfurt am
Main, Germany

Filed June 9, 1961, Ser. No. 65,534

Term of patent 14 years

(Cl. D80—11)

FIG. 1 is a front perspective view of a combined display and merchandising rack for lipsticks or the like showing my new design;

I claim:

The ornamental design for a combined display and merchandising rack for lipsticks or the like, substantially as shown.
